(57) **CLAIM**

The ornamental design for a screwdriver box, as shown and described.

DESCRIPTION

FIG. 1 is a front perspective view of a screwdriver box showing my new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and,

FIG. 8 is a front view thereof in using condition.

The broken line showing of FIG. 8 is for illustrative purposes and forms no part of the claimed design.
